UNITED STATES PATENT OFFICE.

ELIZABETH A. WINDELE, OF SAN FRANCISCO, CALIFORNIA.

DESIGN FOR A STATUE.

Application filed July 22, 1925. Serial No. 14,184. Term of patent 3½ years.

To all whom it may concern:

Be it known that I, ELIZABETH A. WINDELE, a citizen of the United States, residing in the city and county of San Francisco, State of California, have invented a new, original, and ornamental Design for a Statue, of which the following is a specification, reference being had to the accompanying drawing, forming a part thereof.

I claim:

The ornamental design for a statue as shown.

ELIZABETH A. WINDELE.
